US0D1042907S

(12) **United States Design Patent** (10) Patent No.: **US D1,042,907 S**
(45) Date of Patent: ** Sep. 17, 2024

(54) **VEHICLE LIGHT**

(71) Applicant: **NIO TECHNOLOGY (ANHUI) CO., LTD**, Hefei (CN)

(72) Inventors: **Kris Tomasson**, Munich (DE); **Colin Phipps**, Shanghai (CN); **Yuzhou Ling**, Shanghai (CN); **Jeasoo Kim**, Shanghai (CN); **Dongyi Fan**, Shanghai (CN); **Frederik Dallmeyer**, Munich (DE)

(73) Assignee: **NIO TECHNOLOGY (ANHUI) CO., LTD**, Hefei (CN)

(**) Term: **15 Years**

(21) Appl. No.: **29/867,331**

(22) Filed: **Oct. 20, 2022**

(30) **Foreign Application Priority Data**

(57) **CLAIM**

We claim the ornamental design for a vehicle light, as shown and described.

DESCRIPTION

FIG. 1 is a perspective view of a vehicle light;
FIG. 2 is a front elevation view thereof;
FIG. 3 is a rear elevation view thereof;
FIG. 4 is a left side elevation view thereof;
FIG. 5 is a right side elevation view thereof;
FIG. 6 is a top plan view thereof;
FIG. 7 is a bottom plan view thereof; and,
FIG. 8 is a front view of the vehicle light shown in use.
The deemphasized portions in FIG. 8 show environmental structures and form no part of the claimed design.

1 Claim, 5 Drawing Sheets
